INFANT'S SWIVEL CHAIR

Anna E. Trebilcock, Normandy, Mo.

Application May 29, 1957, Serial No. 46,393

Term of patent 14 years

(Cl. D15—1)

FIG. 1

FIG. 2

FIG. 3

FIG. 4

Fig. 1 is a top plan view of an infant's swivel chair embodying the present invention,

Fig. 2 is a front elevational view thereof showing an opening through which the legs of an infant may extend,

Fig. 3 is a left side elevational view showing the seat tilted in one direction, and

Fig. 4 is a right rear elevational view showing the seat tilted in another direction.

What I claim is:

The ornamental design for an infant's swivel chair, substantially as shown.
